UNITED STATES PATENT OFFICE.

LIONEL LANCASTER FARRER, OF FORT WILLIAM, ONTARIO, CANADA.

FOLDING AND ADJUSTABLE CHILD'S SEAT.

1,239,470.

Specification of Letters Patent. Patented Sept. 11, 1917.

Application filed May 10, 1916. Serial No. 96,563.

To all whom it may concern:

Be it known that I, LIONEL L. FARRER, a subject of the King of Great Britain, residing at Fort William, in the Province of Ontario, Dominion of Canada, have invented new and useful Improvements in Folding and Adjustable Children's Seats, of which the following is a specification.

The invention to be hereinafter described 10 relates to a folding and adjustable child's seat.

In order to more clearly disclose the construction, operation, and use of the invention reference should be had to the accompanying drawings forming part of the present application. Throughout the several figures of the drawings like reference characters designate the same parts.

In the drawings:—

20 Figure 1 is a front view of the invention applied;

Fig. 2 is a side elevation of the same;

Fig. 3 is a top plan view of the same;

25 Fig. 4 is an enlarged front view of the seat folded; and

Fig. 5 is a top plan view of Fig. 4.

The main objects of the invention are to produce a simple, efficient, compact, economical, and durable, child's seat which may 30 be easily and quickly collapsed or folded into minimum space and readily adjusted as desired, and also a seat which may be attached and detached as quickly and conveniently as possible.

35 Referring to the drawings in detail, 1 indicates the seat base. Near each end of the base is pivotally mounted an arm formed of heavy wire bent into the form of a broad U with a front vertical branch 2, a rear vertical branch 3, and a connecting branch 4. At the angle formed by branches 2 and 4, the wire is coiled to form a loop or eye 5 for a purpose to be later disclosed. The free end of each vertical arm is slightly off-set 40 inwardly, flattened, and perforated as at 6 for the passage of a small attaching screw, nail, or the like 7. These screws or nails are not driven in tight enough to bind the part 6 against the edge of the base 1. They 45 are left just sufficiently loose to allow the branches 2 and 3 to swing around them as on pivots or pintles, and the off set at the free end of each of these branches spaces them from the edge of the base so that they 50 may be folded down close and compactly on the base 1, as in Figs. 4 and 5. The heads

of the screws or nails, of course, prevent the branches 2 and 3 from slipping off their pivots. Properly speaking, the branches 2, 3, and 4 may be considered together as a single arm at each end of the base 1, and will be so referred to in some of the claims.

The seat, as a whole, is designed to be used as a simple attachment for the ordinary chair to take the place of a high-chair.

65 It is adapted to be suspended from the top rail or a cross rail of the chair back as shown in Figs. 1, 2, and 3. To that end two suspension hooks are provided. From each hook extends a rod 9 the lower part of which 70 is formed as a resilient, extensible coil 10. The inside diameters of the spirals of each coil, when not extended, are substantially the same as the diameter of the branches 3. These coils are disposed about the branches 75

3. Now, when the coil is extended each spiral is contracted to a certain extent and its diameter decreased. This causes a tight binding action between the coil and branch 3, resulting in a solid, friction grip. Or,

80 in the lowest position of the seat, indicated in dotted lines in Fig. 2, the coils are not extended and the seat is held simply by engagement of the upper spiral with the branch 4. If it should be desired to hold 85 the seat somewhat higher than shown, it would only be necessary to lift it so that the strain would be taken off the coils and slide the branches up through the coils until the lower spiral reaches the base 1, for instance, 90 and then extend the upper spirals of the coils by holding the lower spirals while pulling down on the base 1. The upper spirals will then get a frictional hold, as previously explained. In this way, the seat may be 95 held at various heights which is a great advantage.

The pivotal connection of the arms and the attached suspending hooks makes it possible to attach the seat either to a curved 100 back or a straight back chair, as will be readily understood.

The eyes 5 are intended to receive either a strap or the like to prevent a child from tumbling out; or the pintles of the usual 105 swinging shelf common with high chairs. Such devices are well known and therefore it is not thought necessary to illustrate them in connection with the present invention.

110 Preferably, the hooks are covered with rubber tubing or the like 11, to prevent damage to the chair back. A strip of felt or

other buffing material 12 is secured to the rear edge of the base 1 for the same purpose.

It is thought that the construction, operation, and use of the invention will be clear 5 from the preceding detailed description.

Changes may be made in the construction, arrangement, and disposition of the several parts of the invention, within the scope of 10 the appended claims, without in any way departing from the field and scope of the invention, and it is meant to include all such within this application wherein only a preferred form has been shown by way of illustration.

Having described my invention, what I 15 claim and desire to protect by Letters Patent of the United States is:—

1. A child's seat of the character described comprising, a base, arms pivotally secured 20 thereto, extensible coils disposed about said arms and adapted to frictionally grip the same to sustain the weight of the seat, and suspending hooks carried by said coils.

2. A child's seat of the character described 25 comprising, a base, arms secured to the opposite ends thereof and each provided with a vertical branch, a spring coil disposed about each vertical branch and adapted to frictionally engage the same to suspend the seat

at different heights, and suspending hooks 30 carried by said spring coils.

3. A child's seat of the character described comprising, a base, arms secured to opposite ends thereof and each having two branches at right angles to each other, a spring coil 35 disposed about each vertical branch and adapted to frictionally engage the same to suspend the seat at different heights, said coils being also adapted to engage the other branch of each arm when the seat is in its 40 lowermost position, and suspension hooks carried by said spring coils.

4. A child's seat of the character described comprising, a base, U shaped arms pivotally secured to the opposite ends of said base 45 and each consisting of two vertical branches connected by a horizontal branch, and rods provided with suspension hooks at their upper ends and each formed with a spring coil disposed about one of the aforesaid vertical 50 branches and adapted to frictionally engage the same to suspend the seat at various heights, and also adapted to engage the horizontal branch of the arm to suspend the seat in its lowermost position.

Signed at Fort William, Ontario, Canada, this 4th day of May, 1916.

LIONEL LANCASTER FARRER.
